UNITED STATES PATENT OFFICE.

GEORGE WALTER NICHOLSON, OF BUTLER, PENNSYLVANIA, ASSIGNOR OF ONE-HALF TO JOHN F. HUSELTON, OF SAME PLACE.

BILLIARD AND POOL TABLE LEVELER.

SPECIFICATION forming part of Letters Patent No. 591,053, dated October 5, 1897.

Application filed March 25, 1897. Serial No. 629,109. (No model.)

To all whom it may concern:

Be it known that I, GEORGE WALTER NICHOLSON, of Butler, in the county of Butler and State of Pennsylvania, have invented certain new and useful Improvements in Billiard and Pool Table Levelers; and I do hereby declare the following to be a full, clear, and exact description of the invention, such as will enable others skilled in the art to which it appertains to make and use the same.

This invention relates to billiard and pool table levelers; and it consists, essentially, of a specific form of jack comprising two adjustable members supporting a separable ring for engaging the bottom of the leg of the table.

The invention further consists of the details of construction and arrangement, which will be more fully hereinafter described and claimed.

The object of the invention is to secure a very sensitive adjustment by means of a simple and effective attachment which can be easily and readily applied and will not jar or twist the table to which it is applied.

In the accompanying drawings, Figure 1 is a perspective view of a billiard or pool table leg, showing the improved lever applied thereto. Fig. 2 is a transverse vertical central section of the improved device on an enlarged scale. Fig. 3 is a detail perspective view of the parts of the device shown disconnected.

Referring to the drawings, wherein similar numerals of reference are employed to indicate corresponding parts in the several views, the numeral 1 designates a male screw-threaded sleeve which rests upon the floor and is provided or formed with a base-flange 2, with a series of vertically-disposed teeth 3 extend- ing downwardly from the lower portion there- 40 of adjacent to the periphery of said flange. The material inside of the teeth 3 is cut away, as at 4, to permit said teeth to have a firm contact with the surface upon which they rest. The outer surface of the sleeve 1 above the

flange 2 is formed with a series of fine screw- threads extending from the said flange to the upper edge of the sleeve, and adjustably fitting in a collar 5, correspondingly formed with interior female screw-threads. It will 50 be understood that the screw-threads on the outer surface of the sleeve 1 are male threads,

and by turning the collar 5 the latter is raised or lowered and will at the same time raise or lower the table-leg to which the device is applied. To facilitate the rotation of the sleeve 55 1, vertically-disposed lugs 6 are diametrically disposed on the outer surface thereof adapted to be engaged by a spanner to secure the desired adjustment. Separably mounted in the upper part of the collar 5 is a supporting- 60 ring 7, slightly concave in its upper surface to receive the lower end of a leg and having a series of upwardly-projecting peripheral teeth or spurs 8 to take into the leg. The lower side of the said supporting-ring has de- 65 pending therefrom a rib 9, forming a concentric shoulder 10, which is engaged by the up- per edge of the collar 5 in such manner as to have free rotation. The said supporting-ring permits the adjustment of the leg of the ta- 70 ble without disconnecting any of the parts, and also forms an interposed wear-plate be- between the upper edge of the collar 5 and the adjacent portion of the lower part of the leg.

In application the leg of the table is seated 75 in the upper portion of the ring 7, with the teeth 8 bearing thereagainst. The collar 5 is then placed under the ring, and the upper edge thereof engages the concentric shoulder set forth, which prevents lateral movement. 80 The adjustment can then be secured by turn- ing the collar 5 either up or down through the medium of a suitable spanner, as speci- fied, and inequalities in the level of the table may be conveniently rectified by a very sim- 85 ple manipulation. The several parts of the device are adapted to be constructed of suit- able material and ornamented or plated.

It is obviously apparent that many minor changes in the details of construction might 90 be made and substituted for those shown and described without in the least departing from the nature or spirit of the invention.

Having thus described the invention, what is claimed as new is—

In a billiard and pool table leveler, the com- 95 bination of a sleeve having exteriorly-situ- ated fine screw-threads and a lower flange with depending teeth adjacent to the periph- ery thereof, a collar having correspondingly interiorly-situated screw-threads to adjust- 100 ably engage the said sleeve provided with

lugs for turning the same, and a rotatable supporting-ring resting on the upper portion of the collar and entirely separate from the latter and having upwardly-projecting teeth near the periphery thereof and a depending rib forming a concentric shoulder which is engaged by the upper edge of the said collar, substantially as described.

In testimony whereof I have signed this specification in the presence of two subscribing witnesses.

GEORGE WALTER NICHOLSON.
